(57) **CLAIM**

The ornamental design for a bottle identifying device, as shown and described.

DESCRIPTION

FIG. 1 is a front perspective view of a bottle identifying device showing my new design;

FIG. 2 is a front elevational view thereof, a rear elevational view thereof being a mirror image of the front elevational view shown in FIG. 2;

FIG. 3 is a top plan view thereof, a bottom plan view thereof being the same as the top plan view shown in FIG. 3; and, FIG. 4 is a right elevational view thereof, a left elevational view thereof being the same as the right elevational view shown in FIG. 4.
